UNITED STATES PATENT OFFICE.

ALPHONSO COMSTOCK PRATT, OF DEEP RIVER, CONNECTICUT, ASSIGNOR TO WHITING & DAVIS COMPANY, A CORPORATION OF MASSACHUSETTS.

MACHINE FOR MAKING LINK MESH.

1,414,829.

Specification of Letters Patent.

Patented May 2, 1922.

Application filed December 27, 1920. Serial No. 433,184.

To all whom it may concern:

Be it known that I, ALPHONSO COMSTOCK PRATT, a citizen of the United States, residing at Deep River, in the county of Middlesex, State of Connecticut, have invented certain new and useful Improvements in Machines for Making Link Mesh; and I do hereby declare the following to be a full, clear, and exact description of the invention, such as will enable others skilled in the art to which it appertains to make and use the same.

The present invention relates to a machine for making link mesh and has reference more particularly to a machine of this character for forming links and attaching them to mesh fabric, the links of which lie in a plane.

Machines for fabricating link mesh in a plane as heretofore constructed include in one form a set of tools for forming one link at a time, the support for the fabric being shifted step by step after each link forming operation to produce a single row of links intermeshed with the links at the edge of the fabric. In such a machine means are provided to shift the carriage laterally a half step at the beginning of each row to secure the proper spacing of the links.

In another form of machine of this type, a series of tools is positioned at one side of the fabric and a second series, inclined to the first, on the opposite side thereof, the number of tools in each series corresponding to the number of links in a row from edge to edge of the fabric. The tools in each series operate simultaneously to complete a single row of links at a time, the two series of tools alternating in operation, one series acting first to produce a row of links having an inclination in one direction, and the other series then acting to produce a row of links having an inclination approximately at right angles to the links first formed.

Machines constructed as above described differ from the type illustrated, for example, in Letters Patent No. 948,615 granted to me on Feb. 8, 1910, Letters Patent No. 1,028,904 granted to me on June 11, 1912, Letters Patent No. 1,144,724 granted to me on June 29, 1915, and Letters Patent No. 1,317,726 granted to me Oct. 7, 1919, wherein the mesh fabric is in the form of a sleeve

supported on a spirally grooved mandrel. Although in this type of machine it is common to provide a number of tools each forming links in separate grooves to produce a plurality of rows of links, the tools are spaced around the mandrel ninety or one hundred and eighty degrees apart, depending upon their number, all are necessarily positioned on one side of the fabric, and the arrangement of the fabric and tools is otherwise inherently unadaptable for use to fabricate concurrently a plurality of rows of links from edge to edge of a piece of fabric, the links of which lie in a plane.

In the machine of the present invention two or more rows of links may be concurrently produced and added to a piece of link mesh fabric having its links in a plane, and by reason of the fact that at least two rows of links are formed at one time, the links fall in their proper positions with respect to the links at the edge of the fabric without shifting the fabric a half step before beginning the rows of links.

In this machine there is provided the combination of a device for supporting a piece of link mesh fabric with its links in a plane. Forming tools are arranged on one side of the fabric for forming links to intermesh with the links at the edge of the fabric, and forming tools are arranged on the opposite side of the fabric for forming links intermeshing with the links formed by the tools first mentioned. The forming tools cooperate to produce concurrently a plurality of consecutive rows of intermeshing links transversely of the fabric and means are provided for shifting the supporting device and forming tools relatively one to the other to present different portions of the fabric to the tools to receive links. The tools on opposite sides of the fabric may consist of a single set of forming tools on one side of the fabric for forming links intermeshing with the links at the edge of the fabric and a set of forming tools on the opposite side of the fabric for forming links intermeshing with those formed by the first set of tools, both sets of tools forming in one operation a link in each row. Preferably these sets of tools are arranged at an inclination to each other such that the axis of the tools of one set is substantially perpendicular to

the links formed by the other set, by which arrangement the links in one row are oppositely inclined at an angle of approximately ninety degrees with the links in the next 5 adjacent row. Furthermore, the means for shifting the supporting device and the forming tools relatively one to the other may operate to provide a step by step movement after each link forming operation and also 10 to shift the supporting means after the completion of a double row of links to present different portions of the fabric to the tools to receive links. In the embodiment of the invention hereinafter described the supporting 15 device is shifted relatively to the forming tools.

The machine may be constructed to embody the combination of a carriage including a roller for supporting a piece of link mesh 20 fabric with its links in a plane and link forming tools arranged on opposite sides of the fabric; and a pawl may be provided for actuating the carriage step by step transversely of the fabric after each link forming 25 operation, together with means preferably consisting of a cam, for rotating the roller to move the fabric at completion of the rows of links. The pawl may actuate the carriage step by step in one direction 30 transversely of the fabric after each link forming operation, and the machine may include means for returning the carriage in the opposite direction, and a cam carried by the roller which is engaged by a cam actuating member at the end of the return movement 35 of the carriage to rotate the roller whereby the edge of the fabric is presented to the tools.

In the specific embodiment of the invention 40 described hereinafter the link forming tools arranged on opposite sides of the fabric are inclined to each other and spaced so as to form in one operation a link in each row and to add to the fabric concurrently 45 two rows of links. The carriage has a rack which is engaged by a pawl to actuate the carriage step by step in one direction transversely of the fabric after each link forming operation, and means are included for returning the carriage in the opposite direction. Furthermore, a cam is provided which 50 is engaged by a cam actuating member at the end of the return movement of the carriage to rotate the roller whereby the edge 55 of the fabric is presented to the tools.

The embodiment of the invention which is at present preferred is illustrated in the accompanying drawings in which Fig. 1 is a plan view of the machine; Fig. 2 a sectional elevation of the machine taken along the line 2—2 of Fig. 1; Fig. 3 is a plan view of one of the sets of link forming mechanism shown in Fig. 2; Fig. 4 illustrates the mesh fabric formed on the machine, and Figs. 5, 6 and 7 illustrate a modification in the ar-

rangement of the link forming tools, Fig. 5 being a fragmentary and sectional plan view of both tools, Fig. 6 a sectional elevation along the line 6—6 in Fig. 5, and Fig. 7 an end view, in the direction of the arrows, of one of the tools.

The machine is supported on a bed plate 1 having standards 2 positioned near one end of the bed plate, and a central frame 3 extending laterally thereof. The standards 2 are provided with bearings 4 in which is journaled a power shaft 5, the latter having a belt pulley 6 at one of its ends whereby it may be connected to power. The frame 3 has inclined upper faces supporting the tables 7 on each of which is mounted a set of link forming tools. These tools are operated by shafts 8 journaled in bearings secured to the tables 7. The shafts 8 are driven by the power shaft 5 through upright shafts 9 and the bevel pinions with which each of the shafts is provided.

The machine is equipped with two sets of link forming tools such as are illustrated and described in Letters Patent 1,317,726 issued to me on October 7th, 1919. The tables 7 forming parts of each unit are inclined to each other at an angle such that the axis of operation of the link forming dies of one unit is substantially perpendicular to the links formed by the tools of the other unit. Such details of the devices comprised in each unit, as are omitted herein, will be found illustrated and described in full in said Letters Patent above specified.

Fixed to the operating shaft 8 is a cam 10 which actuates the mechanism for feeding wire to the forming tools. This cam operates a slide rod 11 to the right in Fig. 3, the return movement of the rod being effected by a spring 12, one end of which is secured to the rod and the other to a block 13 in which it reciprocates. Mounted to reciprocate in a block 13 is a slide 14 having an inclined face which coacts with the inclined face at the end of the slide rod 11 to produce a downward movement of the slide 14, in Fig. 3, when the slide rod is moved to the right. The slide 14 is returned by a spring 15 acting between it and the block 13. The wire from which the links are formed passes between two friction wheels 16, one above the other, both having grooved peripheries to receive the wire and being geared together as at 17. The upper wheel 16 is pressed down upon the lower wheel by an adjustable spring (not shown) and a ratchet wheel 18 is secured on the same shaft with the lower wheel 16. The ratchet wheel 18 is actuated by a pawl 19 pivotally mounted on the slide 13, the pawl being held against the ratchet by a spring 20. When the slide 14 is actuated by the slide rod 11, the pawl 19 engages the teeth of the ratchet wheel 18, rotates the shaft on which the

lower wheel 16 is secured, and a length of the wire sufficient to form one link is fed to the forming tools, the wire passing through guides 21 located one on either side 5 of the wheels 16.

Fixed to the shaft 8 is a cam 22 encircled by a strap 23 which is secured to a cross head 24 mounted to slide in a block 25. The cross head 24 carries a yoke 26 fitting 10 between flanges 27 on a cylindrical housing 28. Within this housing is a die rod 29, the end of which is threaded into the end of the housing. A coiled spring (not shown) encircles a portion of the die rod, one end of 15 this spring bearing against the end of the housing and the other end against a plunger 30. The plunger 30 consists of a cylindrical portion 31 and a tubular member 32 threaded into the end of the cylindrical member. 20 The tubular member 32 is made up of two parts which are locked together in adjusted position relative to the cylindrical member 31 by a locknut 33. The nut 34, adjusted on the exterior threads of the tubular member 32, is locked in position by a locknut 35 to form a stop. The inner end of the plunger 30, that is, the end of the member 32, passes 25 through an opening in a block 36, which opening corresponds in shape to the cross sectional shape of the end of the member 32. In a threaded opening at the top of the block 36 is mounted an adjustable stop 37 which coacts with the stop formed by the nuts 34 and 35 to limit the forward movement 30 of the plunger. Each of the two parts of the tubular member 32 has secured thereto at its extreme end a spring finger 38 and the die rod 29 carries a die 39, the spring fingers 35 projecting slightly beyond the die and having grooves in their ends for engaging the wire.

Cooperating with the die 39 is an inner die 40 which is mounted in the upwardly extending portion 41 at one end of the slide 45 42, the latter passing through a block 43 secured to table 7. The opposite end of slide 42 carries a cylinder 44 having a threaded opening therein for receiving the threaded end of a yoke 45 in which is mounted a roller 50 46 in engagement with a cam 47 fixed to the shaft 8. The slide 42 is moved to the right in Fig. 3 by a spring 48, and to the left by the action of the cam 47 on the roller 46.

Pivotedly mounted beneath the table 7 is a 55 lever 49, the upwardly bent portion of one side of which carries an anvil 50. The anvil 50 is normally held in a raised position by a spring pressed plunger 51 set in the table 7. The anvil 50 is depressed by a cam 52, 60 on shaft 8, which acts through a plunger 53 set in the table 7, and the crank 54, to turn the lever 49 about its pivot against the spring pressure of the plunger 51.

Mounted to reciprocate in the block 36 is 65 a slide 55 which is moved to the left in Fig.

3 by a cam 56 on the shaft 8, and to the right by a return spring 61. The cam 56 actuates a slide rod 57, reciprocating in a block 58, and having at its end an adjustable extension 59 for engaging one end of a lever 60 pivoted 70 on table 7, the other end of which operates the slide 55. The slide 55 has a slot 62 through which an additional guide 63 for the wire projects. The end portion of the slide 55 has a dove-tail groove 64 in which the knife for cutting the wire is inserted. The slot 62 is of a size permitting a range of action of the slide 55 sufficient for the cutting operation. Opposite the guide 63 is a spring pressed pin 65, mounted in the 80 block 36, and against which the end of the wire abuts when it is fed to the dies by the friction wheels 16.

In forming a link, the wire is fed across the path of the dies and adjacent the anvil 85 50. A length sufficient to make a link is then cut off by the knife carried by slide 55 and the severed wire is held in position by the spring pressed pin 65 while the plunger 30 is advanced to engage the wire. The wire is 90 engaged by the spring fingers 38 and pressed about the anvil 50 by the die 39 taking the form of a staple. The anvil is then depressed and the cooperating inner die 40 advances to engage the ends of the staple and 95 form a closed link. In order to insure simultaneous retractile movement of the die rod 29 and the plunger 30 after the link forming operation the lever 66 pivoted on the table 7 is provided. The lever 66 is actuated by a cam 67 on the shaft 8 which operates a slide rod 68 reciprocating in a block 69. The end of the slide rod 68 is adjustable and engages one arm of the lever 66, the other arm of which acts upon the stop 100 formed by the nuts 34 and 35 to force back the plunger 30, and particularly the portion 105 32 thereof carrying the spring fingers.

In this machine the two sets of link forming tools, arranged on opposite sides of the 110 fabric and inclined to each other, operate as described to form links, and to provide concurrently two transverse rows of links which are added to a piece of mesh fabric. Two links are formed in one operation of 115 both link forming units; as the links 70 and 71 shown in dotted outline in Fig. 4. This necessitates that the link forming tools of one unit be positioned to one side and above those of the other unit, the relative positions being such that the upper link 71 is formed to intermesh with the links at the edge of the fabric, while the lower link 70 is formed to intermesh with the two last 120 links formed by the upper tools immediately preceding the operation in which both links 70 and 71 are formed. The rows produced by the successive links thus formed will have a link 72, shown in dotted outline, outside 125 the edge of the fabrics at the beginning of 130

the operation, and a link 73 (shown in dotted outline) outside the edge of the fabric at the end of the operation, which must be discarded. In order to impart the necessary movements to the link mesh fabric to secure the addition of the links in their proper places as they are formed by the forming tools, the following mechanism is provided.

The link mesh fabric 74 is suspended from a roller 75 the surface of which is formed with a plurality of ridges and depressions which engage corresponding ridges and depressions in the fabric. The roller 75 is mounted on a shaft 76 the ends of which are supported in bearings 77 on a carriage 78. The carriage 78 is set in a guide plate 79 suitably supported on the bed plate 1 of the machine. The carriage 78, and roller 75 mounted thereon, are advanced step by step a distance equal to the diameter of a link after each link forming operation, and this step by step movement is effected by means of a pawl 80 which is in engagement with a rack 81 in a groove on the under side of the slide. The pawl 80 is carried by one end of a link 82 pivoted at 83, the other end of which is actuated by the raised cam surface 84 on the cam wheel 85, the latter being fixed to one of the operating shafts 8. At one end of the machine are two levers 87 and 88 pivoted respectively at 89 and 90 in suitable supports 91 and 92. The ends of each of these levers are provided with yokes 93 fitting between flanges 94 on sleeves 95, the latter being mounted to slide on but not to rotate with shafts 8 and the lever 87 has connected thereto a link 124 having a hooked end for engaging the pawl 80. At the ends of each of the shafts 8 are loosely mounted sleeves 96 carrying bevel pinions meshing with corresponding bevel pinions on the power shaft 5. Both sets of sleeves 95 and 96 have ratchet teeth in their end peripheries to form clutches. Also pivoted at 89 is a bell crank lever 97 one arm of which is in position to be engaged by the end of carriage 78. The other arm of the bell crank lever 97 is adapted to operate a clutch formed by sleeves 98 and 99 similar in construction to the clutches formed by sleeves 95 and 96. The sleeve 98, loosely mounted on the power shaft 5, has mounted thereon a sprocket wheel 100, and carries at its end a bevel pinion. The sleeve 99, keyed to slide on the power shaft 5 but not to rotate with it, carries flanges 101 between which the operative arm of the bell crank 97 fits. The sprocket wheel 100 is connected to a similar sprocket wheel 101 by means of a chain 125, the sprocket wheel 101 being secured to one end of a sleeve 102, surrounding a stud shaft 103. The stud shaft and its sleeve are supported from the guide plate 79 by means of a bracket 104. Mounted on the other end of the sleeve 102 is a gear wheel 105 which

engages a rack 106 in the under side of the carriage 78.

At the end of the bed plate 1, opposite that on which the levers 87 and 88 are mounted, is a lever 107 pivoted in a bracket 108, 70 and a lever 109 and bell crank lever 110 pivoted in a bracket 111 secured at the side of the guide plate 79. The levers 107 and 109 each has a projecting end portion. The lever 107 is connected to lever 88 by means of a connecting rod 112 and lever 109 is connected to lever 87 by means of a connecting rod 113. The bell crank levers 97 and 110 are connected by a connecting rod 114, the bell crank 97 having an additional arm 115 80 for this connection. Secured to the guide plate 79 is a bracket 116 to which is pivotally secured a cam actuating member 117 having a roller 118 at its end. The member 117 is adapted to engage the cam grooves 85 119 in the periphery of the wheel 120 which is fastened to the end of shaft 76. In order that the roller 118 may be brought in alignment with the cam grooves 119, the member 117 is made adjustable about its pivot by 90 means of a screw 121 passing through a threaded opening in an extended arm 122 of the bracket 116. A flat spring 123 is provided to hold the member 117 against the stop 121. 95

During the link forming operation the carriage 78 and the roller 75 with the link mesh 74 move to the left in Fig. 1. When the last links of the two rows are formed corresponding to links 73 and 86 in Fig. 4, 100 the carriage 78, through engagement with the extended end portions of the levers 87 and 88 rotate these levers about their pivots 89 and 90 respectively and the yokes 93, engaging the flanges 94, force the sleeves 95 105 and 96 out of engagement thus disconnecting the shafts 8 from the power shaft 5 and stopping the operation of the link forming tools. At the same time the rotation of the link 87 about its pivot moves the link 124 110 against the pawl 80 and its hooked end disengages the pawl from the rack 81. The end of the carriage also engages one arm of the bell crank lever 97, the other arm of which acts through the flanges 101 to throw the ratchet teeth on sleeve 99 into engagement with those on sleeve 98. The sleeve 98 is thus connected to the power shaft 5 which rotates the sleeve and the sprocket wheel 100 fixed thereto, thus driving the chain 125 and the sprocket wheel 101. The rotation of the sprocket wheel 101 causes the gear wheel 105 to move the carriage 78 and roller 75 to the right in Fig. 1, and as the carriage reaches the limit of its travel to the right the cam actuating member 117 engages one of the cam grooves 119 in the wheel 120 and rotates the roller 118 an amount such that the fabric is raised sufficient for the attachment of another two rows of links. In this position the 130

carriage engages the projecting ends of the levers 107 and 109, and also one arm of the bell crank lever 110, which then act through connecting rods 112 and 113, and 114, to rotate the levers 87 and 88 and the bell crank lever 97 back to their original position, reconnecting the shafts 8 to the power shaft 5 and disconnecting the sleeve 98 therefrom.

It will be understood from the description that links are formed by the tools, on opposite sides of the fabric, only during the movement of the carriage 78 and roller 75 to the left in Fig. 1 and that when the carriage and roller reach the limit of travel to the right in the return movement, the tools are in position to begin two new rows of links after the rotation of the roller by the cam actuating member 117 coacting with the cam grooves 119. No lateral adjustment of the carriage and roller is therefore required to bring the links in proper position for attachment of new links to the fabric, as by shifting a half step preparatory to beginning the link forming operation, where a single row of links is formed at one time.

For the purpose of retaining the roller 75 in position during the formation of the rows of links there is provided a rod 126, supported at 127 on the guide plate 79. The rod 126 is in register with circumferentially arranged apertures extending longitudinally of the roller 75 and as the carriage 78 and the roller moved to the left in Fig. 1, during the link forming operation, the rod 126 enters one of the apertures and locks the roller against rotation. The rod 126 is of such length that it becomes disengaged from the roller at the end of the return movement to permit the shifting of the roller by the cams to position the fabric for the attachment of additional rows of links.

In the modification illustrated in Figs. 5, 6 and 7 there is shown an arrangement of the link forming units on either side of the fabric whereby the axes of the tools are horizontal instead of being inclined at an angle as in the arrangement illustrated in Fig. 2. Since the details of the mechanism in this arrangement are the same as those hereinbefore described with reference to the units arranged at an angle to each other, they will be understood without further description. It will be observed that in the modified arrangement the tools are spaced relatively to each other so that the respective sets will form a link in each of two consecutive rows.

Suitably fastened at each end of the carriage 78 are upstanding pins 129. These pins are spaced apart a distance substantially equal to the width of the fabric being formed, and the links at the respective edges of the fabric are formed to encircle the pins and so are supported against displacement, during a portion of the raising movement of

the fabric preparatory to its being rolled on the roller 75.

In addition to the pins 129, which are intended to be spaced apart a distance such that the link mesh fabric is held substantially taut, means may be employed to guard against the slipping of the fabric on the roller, or other possible displacement especially during the raising of the fabric in position to receive additional rows of links. Such means preferably consist of a roller mounted above the roller 75 and which is provided with a rubber covering and so positioned that the surface of the covering is in contact with the mesh fabric passing over the roller.

To preclude displacement of the fabric particularly during the link forming operation, the machine may furthermore include in its construction a pair of plates, positioned one on each side of the suspended portion of the fabric, which plates are provided with a plurality of opposing ridges extending laterally of the fabric and fitting the depressions therein. The plates are brought together to engage the fabric and hold it against displacement during the link forming operation, and then separated while the fabric is shifted for the addition of further links. The inward and outward movements of the plates are produced by connection with any suitable means of actuation, such as the driving means or moving parts of the machine.

What I claim is:

1. In a machine for making link mesh, the combination of a device for supporting a piece of link mesh fabric with its links in a plane, forming tools on one side of the fabric for forming links intermeshing with the links at the edge of the fabric, forming tools on the opposite side of the fabric for forming links intermeshing with those formed by the tools first mentioned, said forming tools cooperating to produce concurrently a plurality of consecutive rows of intermeshing links transversely of the fabric and means for shifting said supporting device and said forming tools relatively one to the other to present different portions of the fabric to the tools to receive links.

2. In a machine for making link mesh, the combination of a device for supporting a piece of link mesh fabric with its links in a plane, a set of forming tools on one side of the fabric for forming links intermeshing with the links at the edge of the fabric, a set of forming tools on the opposite side of the fabric for forming links intermeshing with those formed by the first set of tools, both sets of tools forming in one operation a link in each row and cooperating to produce concurrently two consecutive rows of intermeshing links transversely of the fabric, and means for shifting said supporting de-

70

vice and said forming tools relatively one to the other to present the edge of the fabric to the tools to receive links.

3. In a machine for making link mesh, 5 the combination of a device for supporting a piece of link mesh fabric with its links in a plane, a set of forming tools on one side of the fabric for forming links intermeshing with the links at the edge of the fabric, a 10 set of forming tools on the opposite side of the fabric for forming links intermeshing with those formed by the first set of tools, said sets of tools being arranged at an inclination to each other such that the axis 15 of the tools of one set is substantially perpendicular to the links formed by the other set, and both sets of tools forming in one operation a link in each row and cooperating to produce concurrently two consecutive 20 rows of intermeshing links transversely of the fabric, and means for shifting said supporting device and said forming tools relatively one to the other, step by step, after each link forming operation, and also at the 25 completion of the double row of links to present different portions of the fabric to the tools to receive links.

4. In a machine for making link mesh, the combination of a device for supporting a 30 piece of link mesh fabric with its links in a plane, a set of forming tools on one side of the fabric for forming links intermeshing with the links at the edge of the fabric, a set of forming tools on the opposite side of the 35 fabric for forming links intermeshing with those formed by the first set of tools, said sets of tools being arranged at an inclination to each other such that the axis of the tools of one set is substantially perpendicular to 40 the links formed by the other set, and both sets of tools forming in one operation a link in each row and cooperating to produce concurrently two consecutive rows of intermeshing 45 links transversely of the fabric, means for shifting said supporting device relatively to the forming tools, step by step, after each link forming operation, and also at the completion of the double row of links to present different portions of the fabric to the tools 50 to receive links.

5. In a machine for making link mesh, the combination of a carriage including a roller for supporting a piece of link mesh fabric with its links in a plane, a link forming tool 55 for intermeshing links with the links at the edge of the fabric, a second link forming tool for forming links intermeshing with the links formed by the first set of tools, said link forming tools being arranged on opposite 60 sides of the fabric, and operating to form in one operation a link in each row and to add to the fabric concurrently two rows of links, a pawl for actuating the carriage step by step transversely of the fabric,

after each link forming operation, and means 65 actuated by said carriage for rotating the roller to move the fabric at the completion of the rows of links.

6. In a machine for making link mesh, the combination of a carriage including a roller 70 for supporting a piece of link mesh fabric with its links in a plane, a link forming tool for intermeshing links with the links at the edge of the fabric, a second link forming tool for forming links intermeshing with 75 the links formed by the first tool, said link forming tools being arranged on opposite sides of the fabric and operating to form a link in each row in one operation and to add to the fabric concurrently two rows of 80 links, a pawl for actuating said carriage step by step transversely of the fabric after each link forming operation, and a cam for rotating the roller to move the fabric at the completion of the rows of links. 85

7. In a machine for making link mesh, the combination of a carriage including a roller for supporting a piece of link mesh fabric with its links in a plane, a link forming tool for intermeshing links with the links at the 90 edge of the fabric, a second link forming tool for forming links intermeshing with the links formed by the first tool, said link forming tools being arranged on opposite sides of the fabric and operating to form a link 95 in each row in one operation and to add to the fabric concurrently two rows of links, a pawl for actuating the carriage step by step in one direction transversely of the fabric after each link forming operation, 100 means for returning the carriage in the opposite direction, and a cam, carried by said roller, engaged by a cam actuating member at the end of the return movement of the carriage to rotate the roller whereby the edge 105 of the fabric is presented to the tools.

8. In a machine for making link mesh, the combination of a carriage including a roller for supporting a piece of link mesh fabric with its links in a plane, a link forming tool 110 for intermeshing links with links at the edge of the fabric, said link forming tools being inclined to each other and spaced on opposite sides of the fabric so as to form in one operation a link in each row and to add to the fabric concurrently two rows of links, a 115 rack on said carriage, a pawl for engaging said rack to actuate the carriage step by step in one direction, transversely of the fabric, after each link forming operation, means for returning the carriage in the opposite direction, and a cam engaged by a cam actuating member at the end of the return movement of the carriage to rotate the roller whereby the edge 120 of the fabric is presented to the tools. 125

In testimony whereof I affix my signature.
ALPHONSO COMSTOCK PRATT.
